Attorney, Agent, or Firm—Seed and Berry[57] **CLAIM**

The ornamental design for a fish attractor, as shown and described.

DESCRIPTION

FIG. 1 is a front perspective view of a first embodiment of a fish attractor showing my new design;

FIG. 2 is a top plan view of the first embodiment;

FIG. 3 is a bottom plan view of the first embodiment;

FIG. 4 is a right side elevational view of the first embodiment;

FIG. 5 is a left side elevational view of the first embodiment;

FIG. 6 is a rear elevational view of the first embodiment;

FIG. 7 is a front elevational view of the first embodiment;

FIG. 8 is a front perspective view of a second embodiment of the fish attractor;

FIG. 9 is a top plan view of the second embodiment;

FIG. 10 is a bottom plan view of the second embodiment;

FIG. 11 is a right side elevational view of the second embodiment;

FIG. 12 is a left side elevational view of the second embodiment;

FIG. 13 is a rear elevational view of the second embodiment; and,

FIG. 14 is a front elevational view of the second embodiment.
